PLUMBING FIXTURE

Henry Van Der Horst, Chicago, Ill.

Application March 5, 1934, Serial No. 714,154

11 Claims. (Cl. 182—31)

My invention relates to plumbing fixtures, and has among its objects and advantages the provision of an improved floor drain. The invention embodies means actuated by the reverse flow of drainage for preventing such drainage from escaping from the floor drain.

This invention also consists in certain other features of construction and in the combination and arrangement of the several parts to be hereinafter fully described, illustrated in the accompanying drawing, and specifically pointed out in the appended claims.

In describing my invention in detail, reference will be had to the accompanying drawing wherein like characters denote like or corresponding parts throughout the several views, and in which:

Fig. 1 is a top plan view;

Fig. 2 is a fragmentary sectional view taken along the line 2—2 of Fig. 1;

Fig. 3 is a sectional view along line 3—3 of Fig. 2, and

Fig. 4 is a diagrammatic sectional view of a different form.

25 In the embodiment selected to illustrate my invention, I make use of a section of tile 10 comprising a part of the usual drain pipe associated with a floor indicated generally at 12 having its upper surface indicated at 14. The tile is usually made in twenty-four inch lengths with an inside diameter of approximately four inches. Within the tile section 10, I position a tubular section 16 having its outer wall fitting snugly within the tile.

35 Around the upper end of the tubular section 16, I fasten a ring 18 having threaded relation with the section 16 at 20 and provided with an integral flange 22 extending inwardly of the section and an integral flange 24 arranged to lie within the

40 enlarged portion 26 of the tile 10 and embedded in the cement of the floor 12. A sealing ring 28 may be positioned between the upper end of the section 16 and the flange 22.

An inner tubular section 30 is movably positioned within the section 16 and has a flange 32 connected with its lower end arranged to fit against the inner wall of the section 16 with sufficient precision to make a liquid-tight seal. The inner face 34 of the flange 22 fits snugly within the tube 30, but permits free relative movement of the tube, in addition to permitting the necessary movement of air into and out of the space between the tubes 16 and 30.

In Fig. 2, the upper end of the tube 30 has 55 threaded relation with a depending flange 36

formed integrally with a plate 38 having its upper face terminating flush with the floor line 14. Normally the plate 38 rests upon the flange 22. Threads 40 are cut in the inner wall of the flange 36 for receiving the threaded end of a short tube 42 having a flange 44 screwed into its lower end. A sealing ring 46 may be positioned between the upper end of the tube 42 and the plate 38 and a similar ring 48 may be positioned between the upper end of the tube 30 and the plate. 60

I mount a perforated disc 50 within a groove 52 cut in the upper face of the plate 38 to permit drainage to flow into the tube 42 and the drain pipe. Referring to Fig. 2, a fourth tube 54 is movably guided by the flange 44 and carries a 70 flange 56 arranged to rest on the flange 44 to support the tube in the normal position illustrated. The lower end of the tube 54 is enlarged at 58 and is provided with a closure plate 60 cooperating with the enlarged portion to provide a float 75 62. A plurality of semi-circular openings 64 in the tube 54 below the flange 44 permits drainage entering the tube to flow into the drain pipe around the float. I make the openings 64 semi-circular to give them width and short vertical 80 dimensions, thus decreasing the necessary length of the tube 54 while giving the tube the necessary fluid outlet capacity.

In operation, the float 62 is normally positioned as indicated in Fig. 2. However, should backwater rise in the tube 30 to a level sufficient to lift the float 62, the communication between the tube 54 and the tube 30 is cut off as soon as the tube 54 has been lifted sufficiently far to position the openings 64 beyond the lower end of the 85 flange 44. This construction makes the tube 54 and the flange 44 operate as a valve. Thus drainage in the nature of backwater is effectively prevented from flooding the floor 12. 90

Continued upward movement of the tube 54 brings its upper end into engagement with a rubber sealing ring 66 lying against the plate 38. Further increase in the level of the backwater will lift the tube 30 through the medium of the plate 38. In this way my telescopic arrangement of the tube sections prevents the backwater from engaging a fixed abutment, thereby eliminating the danger of breakage due to back pressure. 95

A further important feature resides in the arrangement of the parts to permit elevation thereof to a level above the floor line to indicate a backwater condition in the drain pipe. 105

The disc 50 is made removable to permit access to the tube 54 should it become necessary to re- 110

move any accumulation of waste material which might close the openings 64 or load the float 62.

In installations where it is necessary to accommodate backwater of relatively high level it 5 may be necessary to incorporate more than the one tube 30 illustrated in Figs. 2 and 4. To this end I illustrate in Fig. 4 a construction in which an additional tube 67 is positioned between the tubes 68 and 70 corresponding to the tubes 16 10 and 30, respectively, in Fig. 2. Obviously any number of tubes may be incorporated in a unit.

Without further elaboration, the foregoing will 15 so fully explain my invention that others may, by applying current knowledge, readily adapt the same for use under various conditions of service.

I claim:

1. The combination with a floor having a drain pipe associated therewith, of a telescopic floor drain positioned within the drain pipe and normally occupying a position below the floor line, and float operated means associated with the floor drain constructed and arranged to lift part of the floor drain above the floor level when backwater in the drain pipe rises above a predetermined level, said float operated means including means establishing a closure for the floor drain, to prevent backwater from flooding the floor.

2. A floor drain comprising a telescopic structure constructed and arranged for association 30 with a floor and normally positioned below the floor level, said telescopic structure comprising in part a float mechanism actuated upon reverse flow of drainage to project a portion of the telescopic structure above the floor level.

3. The combination with a floor having a tile section connected therewith for association with a drain pipe, of a tube anchored within said tile, a second tube movably positioned within said first tube, said first tube having a flange connected therewith and arranged for guiding said second tube, said second tube having a flange connected therewith arranged to cooperate with the first tube for guiding one end of the second tube, the other end of said second tube being connected 45 with a plate having one surface terminating flush with the floor, a third tube connected with said plate, said plate having openings to permit drainage to flow into said third tube, a fourth tube movably positioned within said third tube and having a float and a plurality of openings permitting drainage entering said third tube to flow into the second tube and the drain pipe, said fourth tube having a flange engaging a flange carried by the third tube for supporting the float in its 50 normal position, said float being constructed and arranged to rise when the backwater in the drain pipe rises above a predetermined level for shifting the fourth tube and positioning the openings therein beyond the flange associated with the third tube to cut off the normal communication between the third tube and the second tube, said fourth tube being arranged to engage said plate and lift the second tube above the normal floor line upon further 55 increase in the level of the backwater.

4. The combination with a floor having a drain pipe associated therewith, of a tube anchored to the floor, a second tube movably positioned within 60 said first tube, a plate connected with said second tube, a third tube connected with said plate, said plate having openings to permit drainage to flow into said third tube, a fourth tube movably arranged within said third tube, and a float operated valve comprising a part of the third tube

and the fourth tube normally arranged to permit drainage entering said third tube to flow through the first and second tubes and into the drain pipe, said float being constructed and arranged to rise when the backwater in the drain pipe rises above a predetermined level for closing said valve, said fourth tube being arranged to engage said plate and lift the second tube above the normal floor line upon further increase in the level of the backwater.

5. The combination with a floor having a drain pipe associated therewith, of a tube anchored to the floor, a second tube movably positioned within said first tube, a plate connected with said second tube, a third tube connected with said plate, said plate having openings to permit drainage to flow into said third tube, and a float operated valve normally arranged to permit drainage entering said third tube to flow into the second tube and the drain pipe, said float being constructed and arranged to rise when the backwater in the drain pipe rises above a predetermined level for closing said valve.

6. The combination with a floor having a drain pipe associated therewith, of a tube anchored to the floor, a second member movably positioned within said tube, a plate connected with the second member, a third hollow member connected with said plate, said plate having openings to permit drainage to flow through said third member, and a float operated valve device operatively connected with said third member permitting drainage passing through said third member to flow into the drain pipe, said float being constructed and arranged to rise when the backwater in the drain pipe rises above a predetermined level for closing said valve.

7. The combination with a floor having a drain pipe associated therewith, of a tube anchored to the floor, a second member movably positioned within said tube, a plate connected with the second member, a third hollow member connected with said plate, said plate having openings to permit drainage to flow through said third member, and a float operated valve device operatively connected with said third member permitting drainage passing through said third member to flow into the drain pipe, said float being constructed and arranged to rise when the backwater in the drain pipe rises above a predetermined level for closing said valve.

8. The combination with a floor drain pipe, of guide means anchored to the floor, a tube structure normally located below the floor line and movably positioned within said guide means, said tube structure communicating with the drain pipe and constituting an inlet for drainage, and a float-operated valve operatively connected with said tube structure and being normally open, said float serving to move the valve to a closed position when shifted by the reverse flow of drainage, said float-operated valve being shiftable bodily to lift the tube structure above the floor line upon a further rise in the drainage level.

9. The combination with a floor drain pipe, of guide means anchored to the floor, a tube structure normally located below the floor line and movably positioned within said guide means, said tube structure communicating with the drain pipe and constituting an inlet for drainage, said tube structure comprising a plurality of tubes arranged

in telescopic relation, and a float-operated valve operatively connected with said tube structure and being normally open, said float serving to adjust the valve to a closed position when actuated by the reverse flow of drainage, said float operated valve shifting bodily to extend the tube structure above the floor line upon a further rise in the drainage level.

10. The combination with a floor drain pipe, 10 of a guide member anchored to the floor, a telescopic tube structure normally located below the floor line and movably positioned within said guide member, said tube structure communicating with the drain pipe and constituting an inlet 15 for drainage, sealing means between the units of the telescopic tube structure, and a float-operated valve operatively connected with said tube structure and being normally open, said float serving to adjust the valve to a closed position when actuated by the reverse flow of drainage, said float-operated valve being shiftable bodily to extend the tube structure above the floor line upon a further rise in the drainage level.

11. The combination with a floor drain pipe,

of a tube anchored to the floor and communicating with the drain pipe, said tube being positioned below the floor line, a guide flange connected with one end of the tube and extending inwardly of the same, a second tube slidably positioned within said guide flange and in telescopic arrangement with said tube, a supporting plate fastened to said second tube and comprising an inlet for drainage, a third tube fixedly connected with said plate and arranged within the second tube for receiving drainage, a fourth tube telescopically arranged within the third tube and having openings for drainage entering the third tube, said fourth tube being normally positioned to locate its openings below the third tube, and a float fastened to said fourth tube and shifted by the reverse flow of drainage to move the fourth tube relatively to the third tube for positioning said openings within the third tube, to establish a closure, said float being arranged to extend said second, third, and fourth tubes to a position above the floor line upon a further rise in the level of the reversely flowing drainage.
